UNITED STATES PATENT OFFICE.

JNO. HARTSHORN AND DEXTER H. CHAMBERLAIN, OF BOSTON, MASSACHUSETTS,
ASSIGNORS TO JOHN HARTSHORN.

FIXTURE FOR CURTAIN-ROLLERS.

Specification of Letters Patent No. 12,661, dated April 3, 1855.

To all whom it may concern:

Be it known that we, JOHN HARTSHORN and DEXTER H. CHAMBERLAIN, both of Boston, in the county of Suffolk and State of Massachusetts, have invented a new and Improved Method of Hanging and Balancing Window-Curtains, of which the following is a full, clear, and exact description, reference being had to the accompanying drawings, in which—

Figure 1 is a view of the curtain with its fixtures; Fig. 2, an end view of the same; Fig. 3, a transverse section upon the curtain rod; Fig. 4, a longitudinal section upon the line A, A, of Fig. 2; Fig. 5, a view of one of the adjustable sockets on which the curtain revolves.

To enable others skilled in the art to make use of our invention we will proceed to describe the manner in which we have carried it out.

Various devices have been employed for the purpose of balancing window curtains, maps, &c., all of them more or less expensive and requiring care in their manufacture and skill in their application to the curtain.

Our present invention has for its object the maintaining of the window curtain in any position in which it may be placed, and our invention consists in a peculiar form of socket upon which one end of the roller turns, which is made adjustable for the purpose of graduating the amount of pressure upon the rod to the weight of the curtain.

In the accompanying drawings B is the rod to which the curtain is attached,—to one end of this rod is secured the spool C, upon the outer end of which is formed the spindle or center a,—this spindle runs in the socket D which is secured to the window jambs by screws or otherwise as seen in Fig. 1. At the other end there is an adjustable socket E, which is made to bear upon the end of the rod in the following manner. The shank of this socket is bent from the perpendicular as seen in Fig. 1, and rests against the window jamb at the point X, where it is confined by a screw;—this socket

is cup formed as seen in Figs. 1 and 5, and having been centered upon the end of the curtain roller by a suitable guide is forced

into the end of the latter by a blow or otherwise, by which means a circular depression d (Figs. 2 and 4) is formed in the end of 55 the rod. When the curtain is to be hung the socket D, being secured to the jamb, the center a is placed in it, and the socket E is attached to the opposite jamb and the screw f is sufficiently loosened to enable the center 60 g within the groove d to enter the cup h of the socket F, the screw f is then tightened until sufficient friction is produced between the socket and rod to retain the latter in any position in which it may be placed. 65

The curtain may be removed when desired by loosening the screw f,—and by tightening this screw the pressure upon the curtain rod may be increased to any required amount, and the curtain may thus be held 70 in any desired position without springs, balance weights or other analogous contrivances.

F is a cord wound upon the spool C, by means of which the curtain may be raised. 75

The method of attaching the curtain to the rod will now be described.

m is a strip of the form represented in Figs. 2 and 3, which is fitted to a corresponding rebate in the curtain rod, to which 80 it is attached by a cloth hinge n—the end of the curtain is then inserted in the bite between the rod and the strip, and the latter is secured in place by the screws p. If the latter does not hang even, or it becomes necessary, at any time to adjust its position upon the rod it is simply necessary to loosen 85 one of the screws in order to readjust it.

The peculiar method of balancing and supporting the window curtain by means of 90 the adjustable socket E has many advantages, among which may be enumerated, first, its extreme cheapness, the two sockets replacing the brackets heretofore required, and at the same time performing everything 95 before accomplished by the springs, weighted tassels and other contrivances employed; second, the same socket answers for curtains of an ysize and weight; third, it is exceedingly simple and not liable to get out of 100 order.

I do not claim balancing and supporting window curtains by means of friction upon the ends of their rods, but

What I do claim as my invention and desire to secure by Letters Patent is—

The bent socket E pivoting upon the window jamb and secured thereto by means of 5 screws as described, whereby sufficient friction may be placed upon the rod to balance a curtain of any size or weight, without the

use of springs or other contrivances for the purpose.

JOHN HARTSHORN.

DEXTER H. CHAMBERLAIN.
